Primary Examiner — Dana K Weiland*Assistant Examiner* — Kathryn Elizabeth Zieno(74) *Attorney, Agent, or Firm* — Duggins P.A.(57) **CLAIM**

The ornamental design for a valve assembly, as shown and described.

DESCRIPTION

FIG. 1 is a top, front, right side perspective view of a valve assembly showing our new design;

FIG. 2 is a bottom, rear, left side perspective view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front elevational view thereof; and,

FIG. 8 is a rear elevational view thereof.

The broken lines illustrate portions of the valve assembly that form no part of the claimed design.

1 Claim, 8 Drawing Sheets(56)
